DESIGN.

—o—

J. L. SHARP.

GAS STOVE.

No. 17,638.

Patented Aug. 16, 1887

UNITED STATES PATENT OFFICE.

JAMES L. SHARP, OF NEW YORK, N. Y.

DESIGN FOR A GAS-STOVE.

SPECIFICATION forming part of Design No. 17,638, dated August 16, 1887.

Application filed July 6, 1887. Serial No. 243,594. Term of patent 7 years.

To all whom it may concern:

Be it known that I, JAMES L. SHARP, residing in the city, county, and State of New York, have invented and produced a new and original Design for Gas-Stoves, of which the following is a specification, reference being had to the accompanying photograph, forming part thereof, which is a perspective view of my newly-designed gas stove.

A represents my newly-designed stove-body, which consists of the horizontal plate *a* and downwardly-projecting flange *b* thereon. The lower edge of the flange *b* is of the double-ogee form, shown with rounded portion *c* between the ogee portions and with downward projections *d*. Around the face of the flange *b*, near its middle portion, is a row of rounded beads, *e*, and on the upper edge of the flange *b*, where it joins the plate *a*, are a series of symmetrical

openings, *f*, as shown. The plate *a* has a series 20 of variously-shaped openings, *h*, which leave between them a lattice-work of curved bars *i*, as shown.

I claim—

1. The design for a gas-stove herein described, 25 consisting of the plate *a*, having the series of variously-shaped openings *h*, and flange *b*, having the row of beads *e* and downward projections *d*, substantially as shown.

2. The design for a gas-stove herein de- 30 scribed, consisting of the plate *a*, having flange *b*, with double-ogee-shaped lower edge and rounded projection *c* along same, and with the row of beads *e*, substantially as shown.

JAS. L. SHARP.
